CONNECTION BLOCK FOR USE WITH
CARRIER-CURRENT LINE TRAPSMyron J. Brown, Pittsburgh, Pa., assignor to
Westinghouse Electric Corporation, East Pitts-
burgh, Pa., a corporation of Pennsylvania

Application May 28, 1947, Serial No. 751,069

7 Claims. (Cl. 173—328)

1

My invention relates to carrier-current line-traps, such as are inserted as a part of an overhead conductor of an alternating-current transmission-line, for the purpose of permitting the free passage of the 60-cycle or line-frequency currents, while impeding the passage of super-imposed carrier-currents, of a carrier-current frequency or radio-frequency, said carrier-currents being utilized for protective relaying-communication, remote metering or switching, or for other purposes. These carrier-current line-traps consist of choke-coils, made of heavy conductor-cable adapted to carry the full line-currents, this coil being supported on a hollow cylindrical insulating support having a tuning-unit inside of the same, for providing the capacitor-branch of a parallel-resonant carrier-frequency circuit, the other branch of which is the choke-coil itself.

My invention has particular relation to carrier-current line-traps which utilize a plurality of capacitors, of assorted sizes, which may be connected together in various series, parallel, and series-parallel combinations, for controlling the amount of capacity which is effective, and thus provide a means for tuning the trap to the particular carrier-current frequency which is being employed.

Heretofore, such traps have used condenser terminal-boards which had two terminals for each of the capacitors employed in the tuning-unit. It was necessary to make the desired terminal-connections by cutting and fitting jumper-wires, with insulating sleeves to suit, in order to provide the necessary combination of connections, so that selected capacitor-units could be connected in series, parallel, or series-parallel, to make up the desired amount of capacity, according to instruction-charts which were provided by the manufacturer. This procedure consumed considerable time, and required a fair degree of skill on the part of the workmen, and it was a job which had to be done by the user of the equipment, and could not be done by the manufacturer, because there are many different carrier-current frequencies in use in different line-sections of transmission-lines, and it is necessary for the customer, or purchaser of the equipment, to be able to tune the line-trap to whatever carrier-current frequency he may require.

The object of my present invention is to provide a novel form of connection-block, or terminal-board, for such carrier-current line-traps, whereby the terminal-connections may be made quickly and easily, without wires; and can be made with a minimum of skill, from the stand-

2

point of the purchaser; and whereby a connection-block construction is provided which makes it a simple and economical matter for the manufacturer to provide the necessary water-tight or weather-resistant construction which is required of all carrier-current line-traps.

With the foregoing and other objects in view, my invention consists in the systems, connection, combinations, parts, and methods of design and operation, hereinafter described and claimed, and illustrated in the accompanying drawing, wherein

Figure 1 is a longitudinal sectional view of a carrier-current line-trap embodying my connection-block in a preferred or illustrative form of embodiment,

Fig. 2 is a side elevational view of the connection-block, with a part broken away,

Fig. 3 is a top or front plan-view of the block, with the top-plate removed, and with a part broken away,

Fig. 4 is a schematic wiring-diagram of the tuning-unit, and

Fig. 5 is an end-view of the connection-block, with the end-plate removed, and with a part broken away.

In the drawing, my invention is shown embodied in a carrier-current line-trap which comprises an insulating hollow cylindrical coil-support 1 having a choke-coil 8 mounted thereon, and having end-brackets 9 which are adapted to be connected to the transmission-line conductor (not shown). Inside of the hollow cylindrical coil-support 1 is a tuning-unit or capacitor-assembly, extending from end to end within said coil-support, and comprising a plurality of capacitors 10, of assorted sizes or capacity-ratings, and a supporting-rack 11 therefor. One end of this capacitor-assembly is provided with a connection-block 12, whereby different capacitor-connections may be made, according to the required carrier-current tuning.

In the illustrated form of embodiment of my invention, there are six capacitors 10, and the connection-block 12 is provided with seven pairs 45 of terminal-buses 13, one pair for each of the six capacitors, and one pair for the choke-coil 8. Each pair of terminal-buses 13 consists of two straight aligned conductors in end-to-end relation, having nearly abutting inner ends which are insulated from each other, all of said pairs of terminal-buses being in spaced parallel arrangement in substantially a single plane. I also provide a plurality of spaced parallel cross-connectors 14, six such cross-connectors being used in 50 the illustrated embodiment of my invention.

These cross-connectors consist of straight conductors which are disposed substantially in another plane, spaced from the plane of the terminal buses, said cross-connectors extending at an angle (preferably at right-angles) with respect to said terminal-buses. A solid insulating supporting-member or block 15 is provided, having solid separator-portions 16 for spacing and supporting the terminal-buses 13 and the cross-connectors 14 in their respective planes. The crossing-points of the terminal-buses 13 and cross-connectors 14 have pin-receiving holes 17 in the terminal-buses 13, the cross-connectors 14, and the separator-portions 16 of the insulating block or supporting-member 15. A plurality of connector-pins 18 are provided, smaller in number than the number of crossing-points, for making selected connections between various terminal-buses 13 and cross-connectors 14. These connector-pins are shown in the form of headed screws.

In the preferred form of embodiment of my invention, the insulating supporting-member or block 15 has front and back surfaces 21 and 22 (or top and bottom surfaces), which are separated by a thickness greater than the spacing between the plane of the terminal-buses 13 and the plane of the cross-connectors 14, and said insulating supporting-member or block 15 has a plurality of parallel sunken supporting-seats 23, below both its front and back surfaces, for receiving said cross-connectors 14 and said terminal-buses 13, respectively, for spacing the same. This is necessary, in the preferred field of application of my invention, for two reasons, both to provide the insulating creepage-distance or insulation which is provided by the sunken seats 23, and also to make it an extremely simple and economical matter to provide a water-tight construction, by adding suitably gasketed top and bottom plates 31 and 32, respectively, and two end-plates 33.

An effective and economically desirable form of construction of the solid insulating supporting-member or block 15 is shown in Figs. 2, 3 and 5 of the drawing, in which the sunken seats 23 for receiving the cross-connectors 14 are provided by means of a plurality of parallel grooves 34 which are milled or otherwise provided in the front or top surface 21 of the block for receiving the cross-connector 14, as shown in Fig. 5; and these cross-connectors 14 are in the form of metal strips which are suitably held in the bottoms of the grooves 34, as by means of holding-screws 35 (Fig. 3). In the illustrated form of construction of my solid insulating supporting-member or block 15, the other sunken seats 23, for the several pairs of terminal-buses 13, are preferably provided by means of a plurality of holes 36 which are drilled in the block 15, parallel to each other, and spaced from the back surface 22 of the block; and the terminal-buses 13 are in the form of round metal rods, which are held in the holes 36 by suitable holding-screws 37, preferably extending in from the rear of the block, as shown in Fig. 2.

To provide additional insulating creepage-surface or insulation, the cross-connector strips 14 are shorter than the grooves 34 in which they lie, so that the ends of these strips are spaced from the ends of the grooves, as shown in Fig. 3. In like manner, and for the same reason, the outer ends of each pair of terminal-buses 13 are sunken below the end of the hole 36 in which said pair is disposed, and a screw-connection 39 or other means is provided, for connecting a terminal connecting-wire 40 (Fig. 3), or insulated terminal-conductor, to each of said sunken outer-ends of

the terminal-buses 13 within the several holes 36. The terminal connections are shown diagrammatically in Fig. 4, with an illustrative arrangement of connector-pins or screws 18, disposed at various crossing-points, to illustrate a commonly used series connection of five of the capacitors 10. Any extra connector-pins or screws 18 which are not in use, can be kept in suitable holes 41 which are provided in the front ends of the end-plates 33, as shown in Fig. 3.

In the illustrated form of embodiment of my invention, as shown more particularly in Figs. 3 and 4, and nearly abutting ends of the six pairs of terminal-buses 13, which are connected to the six capacitors 10, are disposed in the middle of the connection-block, between the central pair of cross-connectors 14; while the seventh pair of terminal-buses 13, which are connected to the terminals of the coil 8, have their nearly abutting ends displaced to one side of the center, so as to fall between the first and second cross-connectors 14. This form of construction provides a maximum facility for making the kinds of terminal connections which are required, whereby the various capacitors may be connected, either in series with each other, or in parallel with each other, or in series-parallel, in various combinations, across the terminals of the coil 8.

In the use of my invention, it will be observed, from Fig. 1, that the top or front plate 31 of the connection-block is accessible at one end of the line-trap. To make the desired capacitor-connections for the tuning-unit, or to change the terminal-connections for tuning to a different carrier-current frequency, all that is necessary is to remove the top-plate 31, thus exposing the grooved front-surface 21 of the solid insulating supporting-member or block 15. As shown in Figs. 3 and 4, the various cross-connectors 14 are numbered from 1 to 6, and the positions of the various pairs of terminal-buses are lettered from A to G, so that the operator may make the necessary terminal-connections, by the use of a suitable number of connector-pins or screws 18, in the proper places to provide any required amount of capacity for radio-frequency tuning, in accordance with a manufacturer's instruction-chart (not shown), after which the front or top plate 31 is reapplied, and the trap is in condition for use.

I claim as my invention:

1. The combination, with a plurality of pairs of terminal-conductors for a plurality of electrical devices, of a connection-block for connecting said pairs of terminal-conductors in various combinations, said connection-block comprising: a separate pair of terminal-buses for each of said pairs of terminal-conductors, each pair of terminal-buses comprising two straight aligned conductors in end-to-end relation, having nearly abutting ends, insulated from each other, all of said pairs of terminal-buses being in spaced parallel arrangement in substantially a single plane; a plurality of spaced parallel cross-connectors comprising straight conductors disposed substantially in another plane spaced from the plane of the terminal-buses, said cross-connectors extending at an angle with respect to said terminal-buses; a solid insulating supporting-member providing solid separator-portions for spacing and supporting the terminal-buses and the cross-connectors in their respective planes; the crossing-points of said terminal-buses and cross-connectors having pin-receiving holes in the terminal-buses, cross-connectors and separator-

portions; and a plurality of connector-pins, smaller in number than the number of crossing-points, for making selected connections between terminal-buses and cross-connectors.

2. The invention as defined in claim 1, characterized by said insulating supporting-member having front and back surfaces separated by a thickness greater than the spacing between the plane of said terminal-buses and the plane of said cross-connectors, said insulating supporting-member having a plurality of parallel sunken supporting-seats, below both its front and back surfaces, for receiving said terminal-buses and said cross-connectors as the case may be.

3. The invention as defined in claim 1, characterized by said insulating supporting-member having front and back surfaces separated by a thickness greater than the spacing between the plane of said terminal-buses and the plane of said cross-connectors, said insulating supporting-member having a plurality of parallel grooves in at least one of its front and back surfaces for receiving the conductors lying in the corresponding plane.

4. The invention as defined in claim 1, characterized by said insulating supporting-member having front and back surfaces separated by a thickness greater than the spacing between the plane of said terminal-buses and the plane of said cross-connectors, said insulating supporting-member having a plurality of parallel holes parallel to each other and spaced below at least one of said front and back surfaces for receiving the conductors lying in the corresponding plane.

5. The invention as defined in claim 1, characterized by said insulating supporting-member having front and back surfaces separated by a thickness greater than the spacing between the plane of said terminal-buses and the plane of said cross-connectors, said insulating supporting-member having a plurality of parallel holes parallel to each other and spaced below at least one of said front and back surfaces for receiving the pairs of terminal-buses, the outer ends of each pair of terminals being sunken below the end of

45 the hole in which said pair is disposed, and means for connecting a terminal-conductor to each of said sunken outer ends within said hole.

6. The invention as defined in claim 1, characterized by said insulating supporting-member having front and back surfaces separated by a thickness greater than the spacing between the plane of said terminal-buses and the plane of said cross-connectors, said insulating supporting-member having a plurality of parallel grooves in its front surface for receiving said cross-connectors, and said insulating supporting-member having a plurality of holes parallel to each other and spaced below its back surface for receiving the pairs of terminal-buses, the outer ends of each pair of terminals being sunken below the end of the hole in which said pair is disposed, and means for connecting a terminal-conductor to each of said sunken outer ends within said hole.

7. The invention as defined in claim 1, characterized by the nearly abutting ends of different pairs of terminal-buses being disposed between a plurality of different pairs of cross-connectors.
